UNITED STATES PATENT OFFICE.

LEON GENIN, OF CHICAGO, ILLINOIS.

INSULATION-CUTTER.

1,157,214.

Specification of Letters Patent.

Patented Oct. 19, 1915.

Application filed September 23, 1914. Serial No. 863,082.

To all whom it may concern:

Be it known that I, LEON GENIN, a citizen of the United States, residing at Chicago, in the county of Cook and State of Illinois, have invented certain new and useful Improvements in Insulation-Cutters, of which the following is a specification.

This invention relates to a new and improved tool for slitting or cutting the fabric insulation or covering on electric circuit wires. In connecting up such wires to generator poles, the binding screws of distributing heads, and otherwise, it is frequently necessary to strip the insulation from the end portion of the wire so as to expose the naked wire for metal contact.

The object of the present invention is to provide a simple, cheap and efficient tool for longitudinally slitting the insulation so that it may be readily peeled off the wire and laid back, or torn off and discarded.

Another object is to provide a tool of the character mentioned well adapted to operate upon insulated wires of different diameters.

The tool of my invention, its mode of operation and its advantages will be clear from the following description, when taken in connection with the accompanying drawing, wherein I have fully illustrated one practical mechanical form in which the invention may be embodied, and referring thereto—

Figure 1 is a perspective side and plan view of my improved insulation cutter, with a portion of the insulated wire shown in dotted lines in a position to be acted upon by the cutter. Fig. 2 is a longitudinal vertical section, showing the blade in side elevation, and clearly illustrating the manner and means of mounting and adjusting the blade. Fig. 3 is a horizontal longitudinal section, on the line 3—3 of Fig. 2, of the complete tool. Fig. 4 is a somewhat enlarged front end view. Fig. 5 is a detail, in inner side elevation, of the forward end of one of the parallel blade-clamping strips, more particularly showing the chamfered edge thereof, which forms one half of the guide groove for the wire. Fig. 6 is a top plan view, partly in horizontal section, of the complete tool, with the parallel strips separated and the fastening and adjusting devices of the blade partially withdrawn to illustrate the mode of assembling the device.

Referring to the drawings, 10 designates

each of a pair of flat, parallel metal strips that are conveniently, and as herein shown, formed by doubling a single flat strip upon itself in such a manner as to create at the inner ends of the strips an integral, rounded spring base or connector 11. The strips 10, on either side of their forward lower corners, are chamfered or beveled on their inner opposed sides, as shown at 12, thereby forming between said chamfered surfaces a groove of substantially V-shape in cross section, which groove preferably extends somewhat inwardly and upwardly of the lower front corner of the strips.

13 designates a cutter blade that is adapted to be clamped between the parallel strips 10, said blade being preferably pivoted at its rear end on a clamp screw 14, and has its forward lower edge and free end portion beveled and sharpened to provide a cutting edge 15, which cutting edge, as best shown in Fig. 4, is located midway of the groove formed by the chamfered surfaces 12 of the clamping strips. This blade is securely clamped by means of a short bolt 16 passing through the strips 10 and the blade, and having on one end a milled head 17, and on its other threaded end a wing nut 18, by turning which latter the clamping strips 10 can be drawn tightly upon the blade 13.

In order that the tool may be easily adjustable to operate upon wires of different diameters, I have provided a simple means for readily adjusting the depth of the cutting edge 15 relatively to the guide groove in which it is located, such adjusting means, as herein shown, being combined with the forward clamp. The blade 13 is formed with a slot 19, and fast on the bolt 16 is an eccentric 20 that, in the assembled position of the parts, lies within the slot 19 of the blade, as most clearly shown in Fig. 2. The bolt head 17 takes the form of a milled nut mounted upon a squared end 21 of the bolt (Fig. 3), which squared end is then riveted down, as shown at 22. From this it will be seen that to adjust the blade it is necessary only to slightly back off the clamp nut 18, whereupon the eccentric 20 can be turned in either direction by the milled nut 17, to either lower or raise the cutting edge of the blade relatively to the guide groove in which it operates, and when the blade has been adjusted, it is securely clamped by again tightening up the nut 18.

Fig. 5 illustrates the manner in which the

blade can be applied to and removed from the holder. When the clamping devices are loosened or withdrawn, the members of the holder occupy substantially the relative positions shown in Fig. 5, by virtue of the spring base or connector 11, in which position of the parts the blade 13 can be readily inserted or withdrawn.

In the use of the device, the knife blade 10 having been adjusted to the proper depth, the grooved forward end of the tool is engaged with the wire to be stripped, as indicated in Figs. 1 and 4, and the tool is drawn, under a light pressure on the wire, 15 lengthwise of the latter. This causes the forward end of the sharp edge of the blade to penetrate and slit the insulation in an obvious manner, after which the insulation can be laid back, exposing the wire, and 20 readily cut or torn off if necessary. It will be observed that the strips 10 form a combined blade holder and handle, and that their chamfered, lower, forward edges also 25 constitute a guide to hold the tool in proper engagement with the wire during the cutting or slitting operation.

It will be evident to those familiar with the art that the device may be modified in various particulars without involving any 30 substantial change of structure, functions or capabilities therein. Hence the invention is to be understood as bounded only by the scope of the appended claims.

I claim:

35 1. An insulation cutter comprising a pair of parallel strips forming a combined blade holder and handle and having their edges chamfered on their inner opposed sides at one end to form a guide groove, a blade pivotally mounted between said strips with its cutting edge lying in said groove, and means for clamping said strips on said blade.

40 2. An insulation cutter comprising a pair of parallel strips forming a combined blade holder and handle and having their edges chamfered on their inner opposed sides at one end to form a guide groove, a blade dis-

posed between said strips with its cutting edge lying in said groove, means for adjusting the depth of said cutting edge relatively to said groove, and means for clamping said strips on said blade. 50

3. An insulation cutter comprising a pair of parallel strips forming a combined blade holder and handle and having their edges 55 chamfered on their inner opposed sides at one end to form a guide groove, a blade pivotally mounted at its rear end between said strips with its forward cutting edge lying in said groove, means for adjusting the depth of said cutting edge relatively to said groove, and means for clamping said blade between said strips. 60

4. An insulation cutter comprising a pair of parallel strips forming a combined blade 65 holder and handle and having their edges chamfered on their inner opposed sides to form a guide groove, a slotted blade pivotally mounted at its rear end between said strips with its forward cutting edge lying 70 in said groove, a cam mounted in the slot of said blade, means for turning said cam whereby to adjust the depth of said cutting edge relatively to said groove, and means for clamping said blade between said strips. 75

5. An insulation cutter comprising a pair of parallel strips forming a combined blade holder and handle and having their edges chamfered on their inner opposed sides at one end to form a guide groove, a slotted 80 blade pivoted at its rear end between said strips with its forward cutting edge lying in said groove, a bolt extending through said strips and the slot of said blade, a cam fast on said bolt and engaging said slot whereby 85 to adjust the depth of said cutting edge relatively to said groove, a clamp nut having threaded engagement with one end of said bolt, and a cam-shifting nut fast on the others end of said bolt.
